(57) CLAIM

The ornamental design for a closure applied to handbags, as shown and described.

DESCRIPTION

FIG. 1 is a front view of a closure applied to handbags showing my new design; and,

FIG. 2 is a front view thereof shown in a different position. The broken lines illustrate boundaries which form no part of the claimed design.

The faded portions outside the broken lines illustrate structure or features which form no part of the claimed design.

1 Claim, 2 Drawing Sheets
